UNITED STATES PATENT OFFICE.

ARTHUR B. ELDRED, OF PAOLA, KANSAS.

PORTABLE KNOCKDOWN FLOOR.

1,160,155.

Specification of Letters Patent. Patented Nov. 16, 1915.

Application filed March 19, 1915. Serial No. 15,552.

To all whom it may concern:

Be it known that I, ARTHUR B. ELDRED, a citizen of the United States, residing at Paola, in the county of Miami and State of 5 Kansas, have invented a new and useful Portable Knockdown Floor, of which the following is a specification.

The present invention appertains to a portable knockdown floor, and aims to provide a floor structure adapted for use in portable houses, skating rinks, exhibition and amusement tents, and in fact all structures of that kind, the floor being of novel and improved construction whereby the sections or parts thereof may be readily assembled and separated.

It is the object of the invention to provide a portable knockdown floor which may be readily and effectively set up or assembled 20 to provide a firm or solid floor or base, which may be used as a skating rink floor, dancing hall floor, and the like, and which floor may be knocked down so that the parts thereof may be readily transported or stored away 25 within small compass.

The present floor construction is adapted especially for use in amusement parks, fairs, and the like, to enable the structure to be knocked down and shipped readily from 30 place to place, and to enable the parts to be readily assembled in a thoroughly practical and efficient manner to provide a firm floor.

As a more specific object, the invention contemplates the provision in a structure of 35 the nature indicated, of unique means for securing the several parts together, whereby they will be held assembled in a most substantial manner, to resist the strains to which the floor is subjected in use, and without 40 the liability of any of the parts becoming displaced or loosened.

It is also within the scope of the invention to provide a portable knockdown floor having the features above noted, and which 45 is comparatively simple and inexpensive in construction, as well as being convenient, serviceable and practical in its use.

With the foregoing and other objects in view which will appear as the description 50 proceeds, the invention resides in the combination and arrangement of parts and in the details of construction hereinafter described and claimed, it being understood that changes in the precise embodiment of 55 the invention herein disclosed can be made

within the scope of what is claimed without departing from the spirit of the invention.

The invention is illustrated in the accompanying drawings, wherein:

Figure 1 is a plan view of the floor structure, portions being broken away. Fig. 2 is an enlarged transverse section taken on the line 60 2—2 of Fig. 1, portions being broken away. Fig. 3 is an enlarged transverse section taken on the line 3—3 of Fig. 1. Figs. 4 and 5 are 65 sectional details taken on the lines 4—4 and 5—5, respectively, of Fig. 2.

In carrying out the invention, there is provided a longitudinal series of transverse joists 1 and 2, which are disposed in alternate arrangement, and the joists of each set are arranged in pairs. The pairs of joists 1 and 2 are spaced apart at suitable distances, and are parallel with one another. The joists extend to the sides of the floor 75 structure, and are divided intermediate or midway between their ends, to provide the side sections 3. The outer or remote ends of the sections 3 are seated upon longitudinal side sills 4, and the inner or adjacent 80 ends of the joist sections 3 are seated upon a central or intermediate longitudinal sill 5. Other longitudinal sills 6 may be disposed between the sills 4 and 5 for supporting the intermediate portions of the sections 3. 85 These sills 4, 5 and 6 may be placed upon the ground or other base, for supporting the floor, and the sills may be constructed in sections so that the sill sections can be handled readily. A tenon 7 is secured between the inner ends of the joist members of one section 3 of each pair of joists, and is adapted to project between the inner ends of the joist members of the corresponding section 3, for holding the joist sections 3 90 in alinement. It is evident that when the sections 3 of each joist are assembled, the tenon 7 of one joist section is slipped or inserted into the inner end of the corresponding section 3, which will hold the joist 95 sections against transverse separation.

Seated upon the joists are longitudinal rows of floor sections 8 and 9, and the sections 8 and 9 are arranged in alternate rows, as clearly evident by reference to Fig. 1. 105 The sections 8 and 9 of the alternate rows are in staggered arrangement, whereby the abutting ends of the two sets of floor sections are out of alinement or in staggered arrangement. The ends of the floor sections 110

8 abut over and rest upon the joists 2, and the ends of the sections 9 abut over and rest upon the joists 1. These floor sections 8 and 9 may be constructed of boards secured 5 together in any suitable manner.

The central or intermediate row of floor sections 8 which lie above or rest upon the adjacent or meeting ends of the joist sections 3, are provided with lower longitudinal 10 cleats 10 which are seated within upper notches 11 provided in the joint sections adjacent the inner or meeting ends of the joist sections, whereby the cleats 10 of the sections 8 in engaging or seating within the 15 notches 11 will assist in holding the joist sections assembled, to prevent their separation until the central or intermediate floor sections 8 are raised or moved.

Mounted or seated upon the outer or remote end portions of the joist sections 3, are upstanding supports 12, which are provided with depending strips or portions 13 overlapping the joist sections 3, to hold the supports 12 slidably upon the joist sections, and 20 to prevent the supports 12 from shifting longitudinally relative to the entire structure. Secured in any suitable manner upon the supports 12 are seat boards or sections 14 and foot rests or aisles boards or sections 25 15. The seat boards or sections 14 are disposed at a higher level than the boards or sections 15, and the boards or sections 15 are disposed inwardly relative to the seat boards or sections 14. The boards or sections 30 14 provide seats for the spectators or onlookers, and the boards or sections 15 provide foot rests for the spectators, and also provide aisles extending longitudinally of the structure between the longitudinal seats 40 and the floor proper provided by the sections 8 and 9.

Upstanding railing posts 16 have their lower ends inserted between the joist members of the sections 3 between the supports 45 12 and the remote or side floor sections 8, and cables or other members 17 may be stretched between the posts 16 at the opposite sides of the floor proper to divide off the spectators from the persons occupying 50 the floor proper. The boards or sections 15 are raised above the floor proper, and kick boards 18 are set on edge upon the joist sections 3 between the remote or outer floor sections 8 and the posts 16, and will serve to 55 define the sides of the floor proper. The kick boards 18 extend longitudinally of the structure, as will be apparent.

Means are provided for securely fastening the several parts upon the joists, and for 60 holding the joist sections together, the said means being associated with the joists 1 and 2. The securing or fastening means of each pair of joists 1 embodies a pair of cables 19 assembled with the respective joist sections 65 3 and arranged between the pair of joists.

These cables 19 are passed over pulleys or other guides 20 carried by the lower surfaces of the floor sections 8, and the cables 19 are passed under pulleys or guides 21 carried between the joist members of the sections 3 between the floor sections 8. The central or intermediate floor section 8 is provided with pulleys or guides 22 at the opposite sides of the adjacent or meeting ends of the joist sections, and over which the cables 19 are passed. The inner or adjacent end portions of the cables 19 are crossed and extend to the opposite joist sections. The inner end of each cable is provided with a hook 23 engaged to one of a series of rods 24 secured between the joist members of the opposite section 3. The hooks 23 being engageable with the series of rods 24, provides adjustable means for engaging the inner ends of the cables 19 to the opposite joist sections. The outer or remote end portions of the cables 19 are passed under pulleys or guides 25 carried between the joist members of the sections 3 below the supports 12 or adjacent the outer or remote ends of the joist sections, and the outer or remote ends of the cables 19 are attached to rods 26 which are slidably through suitable guides or bearings 27 carried by the respective supports 12. Nuts 28 are threaded upon the rods 26 and bear against the bearings 27.

The securing or attaching means of each pair of joists 2 is similar to the securing means of the joists 1, but there are slight differences between the two sets of securing means. Thus, the securing means of each pair of joists 2 embodies a pair of cables 29 associated with the respective joist sections 3, and passed over pulleys or guides 30 carried by the lower surfaces of the floor sections 9 and under pulleys or guides 31 carried between the joist members of the respective sections 3 between the floor sections 9. The inner end portions of the cables 29 are crossed and extended to the opposite joist sections 3 and the inner ends of the cables 29 are provided with hooks 32 engageable with a series of rods or members 33 carried by the respective joist sections 3, the same as with the securing means of the joists 1. The remote or outer end portions of the cables 29 are passed under pulleys or guides 34 carried by the respective joist sections 3 adjacent their outer or remote ends, and rods 35 are attached to the outer or remote ends of the cables 29 and are passed through bearings or guides 36 carried by the respective supports 12. Nuts 37 are threaded upon the rods 35 and bear against the bearings 36.

In setting up the structure, the joists 1 and 2 are placed upon the sills, and the floor sections 8 and 9, supports 12, railing posts 16 and kick boards 18 are then placed properly upon the joists, and at the same time, the cables 19 and 29 are assembled with the

parts in the proper manner. The hooks 23 and 32 will be engageable with the series of rods or attaching elements 24 to provide for a quick adjustment, as will be apparent, and after the parts have been assembled as above indicated, and as illustrated in the drawings, the cables 19 and 29 are stretched or rendered taut. This readily accomplished and without the necessity of the workman crawling under the floor, since the nuts 28 may be readily tightened at the sides of the structure, which will serve to stretch the cables. The stretching of the cables serve to secure the several parts together in a most effective manner. Thus, it will be noted that the respective cables being rendered taut, will pull the joist sections 3 tightly into abutment with one another, and furthermore the supports 12 will be moved inwardly. This will clamp the floor sections 8 and 9 together for providing a smooth floor surface, and the railing posts 16 and kick boards 18 will also be clamped between the supports 12 and remote or side floor sections 8 to hold the said 25 posts and kick boards in position. The cables being passed over the pulleys or guides of the joists and floor sections in the manner above indicated, will be disposed in a zig-zag arrangement, and when the cables 30 are tightened, they will tend to straighten out, so as to securely clamp the floor sections upon the joists. As a result of the peculiar means of securing or attaching the various parts together, the parts will be held 35 firmly in place, and will not be liable to become displaced or loosened even though the structure is subjected to considerable weight or strains. No bolts or similar securing means are employed for attaching the parts 40 upon the joists, and the securing means of the present device are comparatively simple, and are most expedient and efficient in use.

It will be understood that the structure may be made in various sizes and attention 45 is also directed to the fact that the cables being tightened will clamp the supports 12 upon the joists as well as moving the supports 12 inwardly to clamp the floor sections, railing posts and kick boards in place. It is thus impossible for any of the parts upon 50 the joists to be raised accidentally, and the cables serve to both hold the parts upon the joists, and to clamp them together, and furthermore, to clamp the joist sections together. When the cables are loosened or 55 detached, the parts of the structure may be readily separated, so that the structure may be transported readily, or stored within a small encompass.

60 From the foregoing, taken in connection with the drawings, it is believed that the advantages, attributes and capabilities of the present invention will be obvious to those skilled in the art, without further comment being necessary. The present structure pro-

vides a desirable and efficient portable knock-down floor for use in skating rinks, dance halls, and the like.

Particular attention is directed to the fact that the pulleys or guide members of the 70 floor sections are carried by the intermediate portions of the floor sections, whereby the intermediate portions of the respective floor sections will be drawn downwardly tightly upon the joists, and whereby the end portions of the floor sections of the alternate rows will be clamped between the intermediate portions of the floor sections of the adjacent rows, in order that the ends of the floor sections will be properly clamped in 75 place. It is also to be noted that the cables 19 being attached at their inner ends to the opposite joist sections, will prevent the floor sections and seat supports from shifting, as a whole, upon the joists, and the floor sections and seat supports of one half of the structure will be anchored to the joist sections of the other half of the structure.

Having thus described the invention, what is claimed as new is:

1. A knockdown floor structure embodying a joist, a series of floor sections thereon, and means connecting the floor sections with one another and with the joist and so arranged, that a single adjustment is transmitted, to simultaneously draw the floor sections together and down tightly upon the joist.

2. In a knockdown floor structure, a joist comprising abutting sections, a series of 100 floor sections upon the joist, and means connecting the floor sections with one another and with the joist sections, and so arranged, that a single adjustment is transmitted, to simultaneously draw the floor sections together, and down tightly upon the joist sections, and the joist sections into close abutment.

3. In a knockdown floor structure, joists, 110 floor sections thereon, guide members carried by the joists and floor sections, cables passed over and under the respective guide members of the floor sections and joists, and means for stretching the cables.

4. In a knockdown floor structure, joists 115 each comprising a pair of abutting sections, floor sections upon the joists, guide members carried by the floor sections and joists, a pair of cables associated with the sections of each joist and passed over and under the 120 respective guide members of the floor sections and joists, the inner ends of the cables being attached to the opposite joist sections, and means for stretching the cables.

5. In a knockdown floor structure, parallel joists, rows of floor sections thereon, the floor sections of the respective rows being in staggered arrangement and the ends of the floor sections of alternate rows resting upon alternate joists, and means con-

necting each joist with the intermediate portions of the respective floor sections resting thereon and connecting the intermediate portions of said floor sections together, and arranged, by a single operation, to simultaneously clamp the floor sections together and hold the intermediate portions thereof upon the joists.

6. In a knockdown floor structure, parallel joists, elements slidably mounted upon the remote portions thereof, floor sections upon the joists between said elements, and means operatively connecting said elements and floor sections with one another and with the joists, and operable for drawing said elements together to clamp the floor sections together and at the same time hold the floor sections and said elements tightly upon the joists.

7. In a knockdown floor structure, joists, rows of floor sections thereon, the floor sections of the respective rows being in staggered arrangement and the ends of the floor sections of the alternate rows resting upon

alternate joists, the joists and intermediate portions of the floor sections having guide members, cables passed over and under the respective guide members of the floor sections and joists, and means for stretching the cables.

8. In a knockdown floor structure, joists, elements slidable upon the remote portions of the joists, floor sections seated upon the joists between said elements, guide members carried by the floor sections and joists, cables passed over and under the guide members of the floor sections and joists respectively, and means connecting the remote ends of the cables and said elements for stretching said cables.

In testimony that I claim the foregoing as my own, I have hereto affixed my signature in the presence of two witnesses.

ARTHUR B. ELDRED.
